UNITED STATES PATENT OFFICE.

HERBERT WIDSTRAND, OF CHICAGO, ILLINOIS.

WALL-LIGHT.

1,276,467.

Specification of Letters Patent. Patented Aug. 20, 1918.

Application filed September 29, 1917. Serial No. 194,045.

To all whom it may concern:

Be it known that I, HERBERT WIDSTRAND, a citizen of the United States, residing at Chicago, in the county of Cook and State 5 of Illinois, have invented new and useful Improvements in Wall-Lights, of which the following is a specification.

This invention relates to new and useful improvements in vacuum supports for electric lights, and the principal object of the 10 invention is to provide a supporting bell having a vacuum cup thereon with electric means for creating a vacuum in said cup.

Another object of the invention is to provide 15 a magnet for actuating means for withdrawing air from the cup with means for automatically energizing and deenergizing the same when the current is switched on.

A further object of the invention is to 20 form the device of a few number of parts held together within the bell shaped support by a single strip which is secured within the support by a pair of nuts engaging with the screw threaded socket which receives 25 the electric light bulb.

Another object of the invention is to provide 30 a device of this character which is simple and durable in construction, reliable and efficient in operation and one which can be manufactured and placed upon the market at a minimum cost.

The invention also consists in certain other features of construction and in the combination and arrangement of the several 35 parts, to be hereinafter fully described, illustrated in the accompanying drawings and specifically pointed out in the appended claims.

In describing my invention in detail, reference 40 will be had to the accompanying drawings wherein like characters denote like or corresponding parts throughout the several views, and in which:—

Figure 1 is an elevation of the device located 45 on the wall.

Fig. 2 is a longitudinal sectional view.

Fig. 3 is a like view but taken at right angles to Fig. 2.

Fig. 4 is a section on line 4—4 of Fig. 2.

Fig. 5 is a section on line 5—5 of Fig. 2.

Fig. 6 is a section on line 6—6 of Fig. 2.

Figs. 7 and 8 are details of the spring contacts.

Figs. 9, 10 and 11 are details of the 55 brushes.

In these figures 1 indicates the support made of substantially bell shape and having an opening in its upper end which is to receive the screw threaded end of the electric light socket 2, said bell being secured thereto by the nuts 3. A strip 4 has its upper portion made to fit snugly the upper part of the bell and is held in place against the interior wall of said bell by means of the nuts 3, said strip having an opening 60 therein for receiving the screw threaded end of the socket. This strip has its lower end spaced from the lower part of the bell and said lower end has portions bent at right angles and provided with screw threaded 65 openings to receive a pair of screws 5 which hold a plate 6 to said end, said plate passing transversely across the lower end of the bell and partly closing the same. 7 indicates a rubber bulb having its edges projecting beyond 70 the lower part of the bell and having its upper part engaging the bottom of the plate 6, and 8 indicates a second rubber bulb located within the bell having its bottom provided with an annular flange 9 which is 75 seated on the upper face of the plate 6. A pair of plates 10 and 11 located within the said bulbs secure the same to the plate 6 by means of a screw 12 passing through said plates into a soft metal core 13 of a magnet 80 85 14. By means of the screw 12 the two plates 10 and 11 grip the edges of the bulb between themselves and the plate 6 and the core 13 is also held in position on the plate 11. The magnet is composed of a tube 15 90 having its lower ends screw threaded and receiving a flanged nut 16 which secures the upper part of the bulb 8 between itself and the lower plate 17 of the magnet. 18 indicates the upper plate of the magnet, it being 95 understood that the tube 15 with the plates 17 and 18 form a spool to receive the wire with which the magnet is wound. A coil spring 19 located within the bulb 8 and surrounding the core 13 tends to hold the magnet in its upper position with the core 13 100 projecting therefrom. Said core is provided with a slot 20 which forms a passage between the interior of the bulb 8 and the tube 15 and the upper part of said tube is closed by 105 a valve 21 pivoted to the plate 18 as at 22. The bulb 8 communicates with the bulb 7 through suitable openings formed in the plates 10 and 11, the opening in plate 10 being normally closed by an upwardly open- 110

ing valve 23 secured to the plate 10. The plate 17 of the magnet has a projecting portion on which is secured a rubber block 24 and said block carries a pair of brushes 25. 5 These brushes are made of spring metal and are adapted to spring in two directions. They are each provided with a block 26 at their free ends which is of less width than the ends of the brushes so as to provide a 10 flange 27 on each brush. The brushes are secured to the blocks by suitable screws and they are provided with a nipple 28 which engages the side of the block to prevent turning movement of the brushes on the screws. 15 An insulated block 29 is carried by the strip 4 by engaging suitable lugs formed on said strip, and said block is located adjacent the magnet. Said block is formed with notches in its ends into which engage the bent over 20 ends of metal strip 30. Two of these strips are located on the block and each of said strips has secured thereto a spring contact 31. These contacts are secured to the outer edge of each strip for a certain distance and 25 they then converge as at 32 until they come close to each other where they are bent and carried parallel with each other for a short distance where they diverge and are then bent and have their ends parallel as at 33. 30 The lower ends of said contacts 31 end at the point B and a strip 4' has its lower end bent to engage a notch formed in the lower end of the block 29 and its other end is bent upwardly at an incline and then down- 35 wardly and enters an opening formed in the block 29. Said strip 4' is located between the strips 30 and the end of the inclined part is located directly above the parallel parts 32' of the contacts. The ends of the contacts 31 are provided with extensions 31' which are secured to a rubber block 33 secured to the upper end of the strip 4. A 40 second block 34 is secured to said strip 4 opposite the block 33 and this block 34 carries spring contacts 35. The electric wires 36 leading to the lamp socket are secured to these spring contacts 35. The inner ends of the contacts 35 are provided with converging portions ending in semi-circular 45 portions 36 and from here said strips diverge and have their extreme ends parallel as at 37. Said parallel parts 37 lie between the ends of the contacts 33. A push key 38 composed of a jointed rod having an enlargement 39 mid-way of its ends passes through openings in the blocks 33 and 34 and between the pairs of contacts 31 and 35 and has each end projecting beyond the bell. The contacts 35 are normally held out of 50 engagement with the contacts 31 and when it is desired to create a vacuum in the bulb 7 so as to secure the support to a wall the rod 38 is pushed toward the left so as to force the enlargement 39 into the semi-circular portions 36 of the contacts 35. This

will force said contacts apart and throw their ends into engagement with the contacts 31. Thus a portion of the current will pass down said contacts 31 into the brushes and thus energize the magnet, it being understood that said brushes are electrically connected with said magnet. This will cause the magnet to attract the core so that the magnet is moved downwardly compressing the bulb 8 and forcing the air therefrom 70 through the slot 20 in the core into the tube and by the valve 21 into the bell. As the magnet passes downwardly the brushes will slide down the parallel ends of the contacts 33 until they get to the point B where, due to 75 the spring action they will spring together and engage the strip 4'. As soon as the brushes leave the contacts the current is broken and the magnet is forced upwardly by the spring 19. The brushes will pass up 80 the rod 4' and flanges 27 will engage the upper face of said strip and as said flanges strike the inclined part the brushes will be lifted up above the plane of the contacts 31. On further upward movement of the magnet, 85 said brushes will pass off the end of the strip 4' and will thus drop downwardly into engagement with the parallel parts 32' of the contact. Thus the magnet is again connected with the electric current and it will 90 take its downward movement. Thus the magnet will continue to move up and down as long as the push button is in its left hand position. On the upward movement of the magnet a vacuum is created in the bulb 8 95 so that the valve 33 is raised and the air exhausted from the bulb 7. Thus a vacuum is created in said body so that the same will hold the support to a wall. In a rough wall there is likely to be a leakage between bulb 100 7 and the wall. If this is the case bulb 8 with the magnet will slowly rise as the air leaks into bulb 7. If there is no leakage bulb 8 will remain almost stationary. As 105 magnet and bulb 8 reach the top and before starting on their downward stroke valve 23 will close thus retaining the vacuum in bulb 7 and holding the base to the wall until bulb 8 is again on its upward stroke.

It is thought from the foregoing description 110 that the advantages and novel features of my invention will be readily apparent.

I desire it to be understood that I may make slight changes in the construction and in the combination and arrangement of the 115 several parts, provided that such changes fall within the scope of the appended claims.

What I claim is:—

1. A support for electric lights comprising a casing, a vacuum bulb at the end thereof, 120 and magnetic means for exhausting the air from said bulb.

2. A support for electric lights comprising a casing, a vacuum bulb at the end thereof, 125 and magnetic means for exhausting the air 130

from said bulb, and automatic means for alternately energizing and deenergizing said magnet.

3. A support for electric lights comprising a casing, a vacuum bulb at the end thereof, a second bulb in communication therewith, a magnet having sliding movement on its core to depress said second bulb, brushes connected with said magnet, contacts on 10 which said brushes have sliding movement, said contacts ending at a point above the end of movement of said brushes so that said brushes will leave the contacts, a spring for returning the magnet to normal position, and 15 means for throwing the brushes into engagement with the contacts when said magnet reaches its normal position.

4. A support for electric lights comprising a casing of substantially bell shape, an 20 electric light socket carried at the upper end of said casing, a vacuum bulb carried at the lower end of said casing, magnetic means for exhausting the air from said bulb, means for automatically energizing and deenergizing 25 said magnetic means, and switching means for diverting part of the current to said magnetic means.

5. A support for electric lights comprising a casing of substantially bell shape, a

strip of loop form having its upper end of 30 substantially the same shape as the casing, an electric light socket carried by the casing, means for securing the casing and the strip to said socket, a vacuum bulb connected with the lower part of the strip, and means 35 for creating a vacuum in said bulb carried by the strip within the casing.

6. A support for electric lights comprising a casing, a vacuum bulb at the end thereof, a second bulb in communication therewith, a 40 stationary core within said second bulb and having its upper end projecting therefrom, a magnet engaging said projecting end, means for securing the magnet to the upper end of the second bulb, a spring surrounding the core for holding the magnet in raised position, means permitting the passage of air from the second bulb through the magnet, a valve controlling said means, contact 45 means for energizing the magnet to cause 50 its core to attract it to compress the second bulb, said contact means being broken at the end of the movement of the magnet but being formed again by the upward movement of the magnet caused by the spring, and 55 switch means for controlling the current.

In testimony whereof I affix my signature.
HERBERT WIDSTRAND.
